[57] CLAIM

The ornamental design for a flashing distress signal for vehicles with push button activator and status indicator light, as shown and described.

DESCRIPTION

FIG. 1 is a front elevational view of a distress signal showing our new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a perspective view thereof.

The license plate supporting the signal is shown in broken lines for illustrative purposes only.
